(57) **CLAIM**

The ornamental design for an electric scooter for kids, as shown and described.

DESCRIPTION

FIG. 1 is a first perspective view of an electric scooter for kids showing my new design;

FIG. 2 is a second perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of a portion indicated with numeric 9 in FIG. 1; and,

FIG. 10 is an enlarged view of a portion indicated with numeric 10 in FIG. 1.

The dash-dot broken lines are included to annotate partial views in FIGS. 1, 9 & 10. All other broken lines represent portions of the scooter that form no part of the claimed design. None of the broken lines form a part of the claim.
